CLAIM

The ornamental design for headphone headband support, as shown and described.

DESCRIPTION

FIG. 1 is a perspective view of a headphone headband support showing the new design;
 FIG. 2 is a front view thereof;
 FIG. 3 is a rear view thereof;
 FIG. 4 is a top plan view thereof;
 FIG. 5 is a bottom plan view thereof;
 FIG. 6 is a left side view thereof;
 FIG. 7 is a right side view thereof;
 FIG. 8 is a bottom plan view thereof in which unclaimed portions of the headphone are not shown; and,
 FIG. 9 is a top plan view thereof in which unclaimed portions of the headphone are not shown.
 Portions of the drawings shown in broken lines are parts of the headphone headband support which form no part of the claimed design.
